GRINDING WHEEL TRUING APPARATUS

Benjamin S. T. Bishop, Shrewsbury, and Frank A. Bicknell, Worcester, Mass., assignors to Leland-Gifford Company, Worcester, Mass., a corporation of Massachusetts

Application June 8, 1944, Serial No. 539,358

6 Claims. (Cl. 125—11)

1

This invention relates to improvements in grinding wheel truing apparatus. More particularly it relates to apparatus which may be in the form of an attachment for grinding machines and which can have its diamonds or other truing elements preliminarily accurately set in readiness for a wheel truing operation at the will of the machine operator.

It is an object of our invention to provide a wheel truing apparatus having separately mounted truing diamonds, each separately movable into truing relation with a different face of the cutting edge of the grinding wheel, and each preliminarily set in its mounting means for correct precision traverse of a face of the cutting edge of the wheel when moved by the operator to effect a truing of that face. We provide swinging diamond-carrying arms, each swingable on an axis angularly related to the wheel face which is to be traversed by its diamond. Preferably the arms are mounted on an adjustable member which can be secured on a suitable fixed part of a grinding machine where the attachment, during periods of non-use, will not interfere with the regular and normal operations of the grinding machine. However, the diamond-carrying arms are constantly in readiness to be moved to bring each diamond in succession into truing relation to the grinding wheel when the wheel is in a predetermined position with respect to the work driving spindle.

Another object of our present invention is to provide means on the truing apparatus for micrometer adjustment of the arm-carrying member in directions toward and from the wheel for predetermining the amount to be removed from each wheel face while preserving the preliminarily set angular relation between an arm, its diamond and the particular wheel face which is to be dressed.

Still another object is to provide a diamond setting fixture for preliminary precise setting of each diamond in its swinging arm. A base is provided comparable to the base upon which the truing apparatus is to be mounted on the grinding machine, so that the apparatus may be mounted on this fixture precisely as it will be mounted on the machine. A gage block is mounted on the fixture base and has a forward part formed with faces angularly related as are the faces of the cutting edge of the grinding wheel which is to be trued. Hence the diamond in each swinging arm may be set with relation to the proper gage face of the fixture and will be accurately set with relation to a wheel face when the apparatus subsequently is

2

mounted on a grinding machine. To facilitate the setting of the diamonds without the necessity of micrometric adjustment of the member on which the diamond-carrying arm is mounted, a plate of predetermined thickness is used, it being laid first against one gage surface and then against the other gage surface and the diamonds being adjusted to bear against the plate surface which, in one position, faces one diamond and, in another position, faces another diamond.

It is, moreover, our object to generally improve the structure and operation of apparatus for truing grinding wheels.

In the accompanying drawings:

15 Figure 1 is a plan view of wheel truing apparatus embodying features of our invention, shown mounted on a grinding machine forward of and below the horizontal plane of the grinding wheel axis;

20 Figure 2 is an end elevation of the same with a portion in section on line 2—2 of Figure 1;

Figure 3 is a view similar to Figure 1 but with the diamond-carrying arms swung into truing relation to the grinding wheel;

25 Figure 4 is a plan view of the truing apparatus mounted on the diamond setting fixture; and

Figure 5 is an end elevation of Figure 4 showing one diamond carrying arm in position for setting its diamond with relation to the plate on the gage face.

Referring to the drawings, an improved wheel truing device is shown as an attachment which can be mounted on a grinding machine in readiness to perform a wheel truing operation at the will of the operator. In the embodiment herein illustrated, a base 10 is secured on a suitable fixed part 12 of the machine by the two bolts 14 which are threaded into nuts 16, engaged in a T-slot 18 in the part 12 of the machine. Each

35 nut 16 has a shank 17 which extends out of the T-slot and seats in a recess 20 in the under side of base 10 for ensuring a precision alignment of the base 10 relative to the T-slot 18. The base, between the bolts 14, 14 is formed at 40 its under side with a wide groove 22 for receiving a slide member 24 which extends beyond the base both forwardly as at 26 and rearwardly as at 28. At the forward projecting end of the slide there is mounted a block 30 on whose front face 45 is the setting gage 32. The forward shank end of a screw 34 extends loosely through the gage and block with a graduated knob 36 on its extreme forward end for micrometer adjustment of the slide 24 by bringing particular graduations 50 on the knob into register with a guide edge 38

formed at the cut-out 40 of a plate 42 secured on the top face of block 30. The inner end of screw 34 is threaded into the forward part of base 10 which serves as a fixed nut coacting with the screw for moving the slide relative to the base when the screw is rotated. A vertical threaded stud 46 rises from the slide and extends through a slot 48 in base 10 with a nut 50 on its upper end engaging the large diameter washer 52 for clamping the base and slide together in relatively adjusted positions. When nut 50 is loosened the stud can move in slot 48 to permit adjustments of the slide. A set screw 54 is provided in block 30 for locking screw 34 against accidental rotation after a micrometer setting of the slide.

The rearwardly projecting part 28 of the slide has mounted thereon the two swinging arms 56, 58, each carrying a diamond 60.

At times of non-use, the arms 56, 58 lie flat as in Fig. 1, in crossed relation with arm 58 overlying arm 56 and having a shape for bridging arm 56 while its free end rests flat on the surface 11 of base 10. Assuming a proper preliminary setting of the diamonds 60, and a proper adjusted relation between the slide member 24 and wheel 44, the wheel may be trued by merely causing the diamond-carrying arms 56 and 58 to traverse the faces of the grinding wheel which is being trued.

The preliminary setting of the diamonds in the arms 56, 58 may be accomplished prior to mounting the truing apparatus on the grinding machine. A special fixture is provided comprising a base 70 having a top surface comparable with the machine surface on which the apparatus ultimately is to be mounted. The base 70 has a T-slot 72 out of which the special nuts 16 can project and seat in the recesses 20 in the underside of the base 10 of the truing apparatus, precisely as has been described in connection with the mounting of the apparatus on a machine. The bolts 14 engage the nuts 16 to clamp base 10 on base 70 with the slide member 24 projecting fore and aft of base 10 as previously described.

Base 10, however, projects rearwardly beyond the slide and has mounted on its rear portion the upstanding member 74 on whose top is secured a gage plate 76 having its forward part shaped to provide the angularly related faces 78, 80 corresponding in position and angle to the faces 62, 64 of the grinding wheel 44. Hence, by setting the diamonds 60 in arms 56, 58 for proper traverse respectively of faces 78 and 80, the diamonds will be properly set for truing wheel 44 when the apparatus is mounted on a grinding machine. Preferably, instead of setting the diamonds for traversing the faces 78, 80 of plate 76, a loose bar or plate 82 is provided which can be laid against the faces 78, 80 in succession thereby to project the angle of face so that the diamonds may be set relative to the outer surface of bar 82 without adjusting slide 24.

The herein disclosed simple yet accurately effective means for truing a grinding wheel enables the truing elements, correctly and accurately set, to be ever ready in a non-interfering position, for use when needed.

We claim as our invention:

1. Grinding wheel truing apparatus comprising a fixed gage having a tapered part with faces angularly related precisely corresponding to the angular relation of the bevelled edge faces of a wheel which is to be trued, a horizontal support

below and forward of said gage, a pair of arms pivotally mounted on said support and independently swingable on angularly related axes, a wheel truing element adjustably mounted on each said arm, said arms being adapted to rest on said support in generally horizontal positions below and forward of the gage, and means for swinging one said arm to bring its said truing element to position for adjusting its setting relative to a said gage surface while the other arm continues in its said generally horizontal position.

2. Grinding wheel truing apparatus comprising a fixed gage having a tapered part with faces angularly related precisely corresponding to the angular relation of the bevelled edge faces of a wheel which is to be trued, a horizontal support below and forward of said gage, a pair of arms pivotally mounted on said support and independently swingable on angularly related axes, a wheel truing element adjustably mounted on each said arm, said arms being adapted to rest on said support in generally horizontal positions below and forward of the gage, means for swinging one said arm toward said gage to bring its said truing element into a position for adjustment of its setting relative to said gage while the other arm continues in its said generally horizontal position, and graduated means for adjusting said support toward and from said gage to set the truing element relative to said gage and, subsequently, to set the set truing element in any of various selected positions backward from the position of its setting relative to said gage, thereby to set the truing element for precision truing of a grinding wheel operating on work of any particular diameter.

3. In a grinding machine having a grinding wheel and having a fixed horizontal surface below and forward of the wheel above which surface is the work position of the machine, wheel truing apparatus comprising a horizontal base adapted to be mounted on said fixed horizontal surface below and forward of the grinding wheel, a pair of arms pivotally mounted on said base and independently swingable on angularly related axes, a wheel truing element mounted on each arm, said arms being adapted to rest idly on said base in generally horizontal positions when a grinding operation is being performed by said wheel on work in said work position, and means for swinging one said arm independently of the other arm to bring its said truing element into truing engagement with the grinding wheel when said work position is vacant.

4. In a grinding machine having a grinding wheel and having a horizontal surface below and forward of the wheel above which surface is the work position of the machine, wheel truing apparatus comprising a horizontal base adapted to be mounted on said horizontal surface below and forward of the grinding wheel, a pair of arms pivotally mounted on said base and independently swingable on angularly related axes, a wheel truing element mounted on each arm, said arms being adapted to rest idly on said base forwardly of the grinding wheel and below the said work position when a grinding operation is being performed by said wheel on work in said work position, with one said arm crossing over the other, means for swinging said crossing over arm to bring its truing element into truing engagement with the grinding wheel when said work position is vacant, and means for subsequently swinging said other arm to bring its truing element into truing engagement with the grinding wheel.

5. In a grinding machine having a grinding wheel mounted for rotation about a horizontal axis, wheel truing apparatus comprising a plurality of arms each pivotally mounted for swinging about an axis disposed in a horizontal plane substantially below the horizontal plane of the axis of said grinding wheel, said arms being adapted to rest in idling positions in which both arms extend approximately in the horizontal plane of their axes, with one arm extending across the other, and a truing element on each said arm, each said arm being swingable about its pivot from its said idling position to bring its said truing element into truing engagement with the grinding wheel.

6. In a grinding machine having a grinding wheel rotatably supported for rotation about a horizontal axis, wheel truing apparatus compris-

ing an arm pivotally mounted on a horizontal pivot for swinging movement between an idle position in which the arm rests approximately in the horizontal plane of its axis of swinging forwardly of and below said grinding wheel, and wheel truing positions in which the arm is adjacent peripheral regions of the wheel, a wheel truing element mounted on said arm outward from its axis of swinging, means on said arm for swinging it thereby to cause said wheel truing element to traverse a said peripheral region of the wheel, and graduated means for moving the said arm bodily toward and from the grinding wheel a predetermined amount thereby to set the truing element selectively for truing the wheel working on any of various diameters of work.
